(57) **CLAIM**

The ornamental design for a radio frequency adapter with HDMI port, light, and button, as shown and described.

DESCRIPTION

FIG. 1 is a perspective view of a radio frequency adapter with HDMI port, light, and button showing our new design;

FIG. 2 is a front view thereof;

FIG. 3 is a back view thereof;

FIG. 4 is a top view thereof, the bottom being identical; and,

FIG. 5 is left side view thereof, the right side being a mirror image.

Any broken lines shown represent unclaimed subject matter and form no part of the claimed design.
